TAILSTOCK FOR GRINDING MACHINES

Alden M. Drake, West Hartford, Conn., assignor
to Niles-Bement-Pond Company, West Hartford, Conn., a corporation of New Jersey

Application May 15, 1948, Serial No. 27,267

3 Claims. (Cl. 82—31)

1

This invention relates to grinding machines and particularly to an improved tailstock construction therefor adapted for supporting one end of a work piece on a center for rotation on a fixed axis.

An object of the present invention is to provide a laterally adjustable work supporting tailstock, the lateral adjustment of which can be varied to an extreme precision.

Another object of importance of the invention is to provide a tailstock spindle that may be held in its work engaging position by any one of a series of resilient members having different resiliencies, the pressures of each of which also may be widely varied.

A feature that enables the above objects to be accomplished is that there is provided on the tailstock a turret rotatable upon an axis parallel to the direction of movement of the spindle and housing a plurality of springs or other resilient members any one of which, by rotation of the turret, may be positioned for engagement against the rear end of the spindle in position to force the spindle toward work engaging position.

Another feature of importance is that the pressure exerted by each of these resilient members may be individually adjusted so that a wide selection of pressures may be available by selective engagement of the springs against the end of the tailstock spindle.

With the above and other objects in view the invention may include the features of construction and operation set forth in the following specification and illustrated in the accompanying drawing.

In the accompanying drawing annexed hereto and forming a part of this specification, I have shown the invention embodied in a tailstock adapted primarily for a screw thread grinding machine in which the work is mounted for rotation upon centers in alignment with each other, but it will be understood that the invention can be otherwise embodied and that the drawing is not to be construed as defining or limiting the scope of the invention, the claims appended to this specification being relied upon for that purpose.

In the drawing:

Figure 1 is a front elevation of a complete tailstock made in accordance with the present invention.

Figure 2 is a longitudinal plan view of the tailstock shown in Figure 1, the section being taken upon the planes of broken line 2—2 in Figure 4.

Figure 3 is a vertical cross section of the tail-

2

stock taken on the plane of line 3—3 in Figure 1 and

Figure 4 is a cross section taken on the plane of line 4—4 shown in Figures 1 and 2.

5 In the above-mentioned drawing there has been shown but one embodiment of the invention which is now deemed preferable, but it is to be understood that changes and modifications may be made within the scope of the appended claims 10 without departing from the spirit of the invention.

Briefly and in its preferred aspect, the invention may include the following principal parts: first, a base member adapted for engagement

15 with the ways of a grinding machine bed or table; second, a body member laterally adjustable on said base and having transversely extending ways for engagement with said base; third, adjusting means for varying the lateral position of the body

20 member relative to the base; fourth, a center supporting spindle slidably mounted within said body member; fifth, a turret rotatably mounted at one end of said body member for rotation on an axis parallel to the direction of movement of

25 the spindle; sixth, spring-pressed plungers mounted within the turret and selectively and individually engaging against the end face of the tailstock spindle; seventh, means to adjust the pressures of said plungers, and eighth, means to 30 manually move the spindle in either direction.

Referring more in detail to the figures of the drawing, it will be seen that there is a base 10 adapted for engagement with the guideways of a table or bed 12 of a grinding machine or other form of machine tool and provided with a short vertically extending stud 14. Mounted in transversely extending ways in said base 10, is a body member 16 within which is mounted the tailstock spindle 18.

40 To laterally adjust the position of the body member 16 relative to the base 10 on the transversely extending ways 20, a threaded member 22 is mounted in an inserted member or sleeve 24 in the body member 16. As shown in Figure 4, the threaded member 22 extends horizontally and its inner threaded end engages internal screw threads formed within the stud 14 mounted vertically within the base 10. To provide fine adjustment for the lateral movements of the body member 16, a second or intermediate threaded portion may be provided of the opposite helix and slightly different lead from the threads at the inner end of member 22. This threaded section engages internal screw threads formed within the sleeve 24

45 fitting within and rotatable in a recess formed in

55

the body member 16. A spring detent 26 retains the sleeve 24 normally against rotation but permits manual rotation of the sleeve by means of the knurled flange 28 on its outer end. By rotation of the sleeve 24, the body member will be moved laterally in accordance with the lead of screw threads on the intermediate portion of the threaded member. By rotation of the threaded member 22 by the knob 30 on its outer end, the lateral movement of the body member 16 will be extremely slow as it will be determined by the difference in lead of the two-threaded sections on the threaded member 22.

To retain the body member 16 in adjusted lateral position on the base 10 and to clamp the base 10 and body member 16 to the machine ways 12, a bolt 32 having a head at its lower end entering a T slot in the ways 12 may be tightened by rotation of a hand lever 34 threaded to the upper end of the bolt.

As shown in the figures, the tailstock spindle 18 extends longitudinally and horizontally within the body member 16 and is held in place by a cap member 33 secured to the rear face of the body member.

In order to move the tailstock spindle 18 within the body member 16 in either direction, a plurality of rack teeth 35 are formed in a surface thereon; these teeth engage gear teeth 36 on an intermediate portion of a vertically mounted shaft 38 within the body member 16. As shown in detail in Figure 3, this shaft 38 is mounted upon anti-friction bearings and may be operated by a handle or lever 39 secured to the upper end of the shaft.

In order to resiliently force the tailstock spindle 18 in a direction to engage against the end face of the work piece, with predetermined adjusted pressures, the following mechanism is provided. Mounted on the rear face of the body member 16 is a rotatable turret 40 mounted for rotation upon an elongated shaft 42 threaded into the rear face of the body member 16.

This turret 40 is rotatable about an axis parallel to the direction of movement of the spindle 18 and houses a plurality of longitudinally extending springs 44. To manually rotate the turret 40 about its axis it is only necessary to grasp the outer knurled portion 46 of the turret. The opposite ends of each spring 44 extend within hollow plungers 46. The forward ends of the springs 44 within its plunger except one are in engagement with the end face of the body member 16 only and are therefore inactive. One spring as shown in Figure 2, bears against the spindle 18 and by rotating the turret 40 any selected one of the different springs 44 may be brought into this spindle engaging position. In the forward position of the spindle 18 the plunger 46 for the active spring 44 also bears partially against the end face of the body member 16 and limits the forward movement of the spindle. As each spring 44 is of different resiliency or pressure, by selecting the proper rotative position of the turret 40 the spindle 18 may be forced to-

ward its work engaging position with any desired pressure.

To individually adjust these springs 44 to get additional variable pressures, the plungers 46 housing the rear end of each spring bear against an adjusting screw 48 threaded into the end plate of the turret 40. By adjustment of the screw 48 for any spring 44, the compression of the individual springs may be widely varied.

10 To normally but lightly force the body member 16 in one direction relative to the base 10, one or more light spring pressed plungers 50 may be mounted within the base with its outer end bearing against a depending portion of the body member 16.

I claim:

1. A tailstock for grinding machines comprising, a body member, a spindle slidably mounted therein, manual means to move said spindle longitudinally within said tailstock, a turret rotatably mounted on said tailstock on an axis parallel to the direction of movement of said spindle, and a plurality of springs mounted within said turret for selective engagement against an end face of said spindle, whereby the pressure exerted against said spindle may be varied by positioning a selected spring against said spindle.

2. A tailstock for grinding machines comprising, a body member, a spindle slidably mounted therein, manual means to move said spindle longitudinally within said tailstock, a turret rotatably mounted on said tailstock on an axis parallel to the direction of movement of said spindle, and a plurality of helical springs mounted within said turret for selective engagement against said spindle and extending in the direction of movement of said spindle, whereby the pressure exerted against said spindle in one direction may be varied by positioning a selected spring against said spindle.

3. A tailstock for grinding machines comprising, a body member, a spindle slidably mounted therein, manual means to move said spindle longitudinally within said tailstock, a turret rotatably mounted on said tailstock on an axis parallel to the direction of movement of said spindle, a plurality of springs mounted within said turret for selective engagement against said spindle, whereby the pressure exerted against said spindle may be varied by positioning a selected spring against said spindle, and individual adjusting means for varying the force exerted by said springs.

ALDEN M. DRAKE.
